UNITED STATES PATENT OFFICE.

JOHN L. McMILLAN, OF SYRACUSE, NEW YORK.

LOOSE-LEAF BINDER.

No. 857,254.

Specification of Letters Patent.

Patented June 18, 1907.

Application filed June 11, 1906. Serial No. 321,257.

To all whom it may concern:

Be it known that I, JOHN L. McMILLAN, a citizen of the United States, residing at Syracuse, in the county of Onondaga and State of New York, have invented certain new and useful Improvements in Loose-Leaf Binders, of which the following is a specification.

This invention consists in a novel construction of loose-leaf binders, hereinafter fully set forth and pointed out in the claims.

The invention is illustrated in the accompanying drawing, in which Figure 1 is a perspective view of the binder with the cover-boards and cap-plate partially broken away; Fig. 2, a transverse sectional view showing the parts in the position which they occupy when the binder is in use and the impaling rings are closed; Fig. 3, a similar view with the rings opened; Fig. 4, a longitudinal section through a portion of the binder mechanism; Fig. 5, a perspective view of the cap or cover-plate for said mechanism; Figs. 6 and 7, side and top views of the impaling ring joint; and Fig. 8, a perspective view of one of the springs employed to retain the impaling rings in their opened or their closed position, as required.

The purpose of this invention is to produce a simple and efficient device which may be manufactured at small cost, and which shall operate easily and maintain the impaling rings in their opened and closed positions with certainty.

Referring again to the drawings, A and B indicate cover-boards of any suitable character, which may be made in one piece with or attached to an intermediate back member C.

D indicates a concavo-convex stay or stiffener for the back, preferably of rigid sheet metal, but which may be of other suitable material, and secured in any convenient way to the back C.

E indicates a lining or facing, which may be of leather, cloth, or other suitable flexible material, and which is in the preferred construction of the binder carried over the inner faces of the cover-boards and of the stay or stiffener D, being also preferably carried about the edges of said stay and somewhat under the same, as indicated in Figs. 1, 2 and 3. This lining may, however, be omitted or may be applied only to the cover-boards, but it serves, when used, to improve the appearance of the binder and also to strengthen the attachment of the stay or stiffener. The

lining is cemented to the cover-boards and stay or stiffener.

F indicates a trough-shaped support for the impaling rings G, which rings consist of two members a and b, hinged or jointed at one side and capable of being opened or separated at the other side, as is common in this class of binders. The support F has its longitudinal edges inturned or curled over to form barrels which receive pivot-rods c, on which the members a, b of the impaling rings G rock or swing when being opened or closed. Midway between the rods c and within the trough-like support F are the joints by which the members a, b are connected, a single rod or wire d passing through the several sets of ring members and constituting a pivot or joint pin for all, as will be understood upon referring to Fig. 1.

It is desirable that the members a, b of the rings G be prevented from opening too far, and with this end in view the joints are made as shown in Figs. 6 and 7, that is to say, they are knuckle-joints, having stop faces e and f, the engagement of which with each other limits the opening of the rings, as seen in Fig. 6.

The rings G are held at the proper distances apart and are prevented from shifting by being seated in notches cut in the barrels g of the support F, and further by a cover-plate H of the form shown in Fig. 5, which is sprung into binding or holding relation to the trough-like member F, as shown in Figs. 1, 2 and 3, and which is similarly provided with notches h to allow proper play of the rings G in opening and closing. Longitudinal movement of the cover-plate H is precluded by reason of the rings extending into the slots or notches h. The support F is made fast to the stay or brace D in any convenient way, as, for instance, by eyelets or tubular rivets i, Figs. 1, and 4.

I indicates a spring formed with a flattened loop j and with two branches k, which lie parallel or substantially parallel with each other for a distance and then curve outward and downward, as shown in Figs. 1, 2, 3 and 8. The space between the parallel faces of the members k is made somewhat narrower than the thickness of rod or wire d, which can therefore be passed through said space only when some appreciable or considerable force is applied for the purpose. In practice I employ, preferably, as many springs I

as there are impaling rings G, said springs being placed in the trough-like support F, with their flattened loops j resting upon the bottom of the trough and the outer or free ends of their branches extending to and resting upon the barrels g of said support, or extending nearly thereto. The number of springs, I, may vary and in practice from one upward may be employed. When the cap or cover-plate H is applied, it bears upon the upper convex faces of the branches k and thus holds the springs firmly in place.

The relation of the springs, the pivot-rods c and the hinge-rod d will be seen and understood upon reference to Figs. 2 and 3. In Fig. 2 the parts are in the position which they occupy when the rings are closed, the rod or wire d being then in the flattened loop j and just at the mouth of the parallel walled

22 passage between the branches k of the spring.

In Fig. 3 the rings are shown opened or separated and the rod d has forced apart the parallel walls of the branches k of the spring and passed upward to a point where the 25 branches begin to curve outward or away from each other. The resilience of the springs tends to hold the rod or wire d in whatever position it may be given through the opening or closing of the rings. Owing 30 to the leverage afforded by the longer outer arms of the members a, b, as compared with their inner arms, adequate power can be applied readily to force the rod or wire d through the narrow passage from one position 35 to the other.

The construction thus set forth is at once simple, cheap and efficient, and all the parts can be produced by machinery rapidly and at small expense.

40 The stay or stiffener D is not essential and may be omitted. Its use is, however, quite desirable since it gives greater strength and stiffness and better form to the back, and serves also as an additional stop to limit the 45 opening of the rings G, the members a, b, of which when fully opened engage with or rest upon the edges of said stay, as indicated in Fig. 3.

Having thus described my invention, what 50 I claim is:—

1. The herein-described binder comprising a back and cover-boards, a stiffener secured thereto; a trough-like support secured to said stiffener; rings G comprising members a, b pivotally mounted upon said support; rod or wire d passing through proximate

5 ends of said ring members and forming a hinge or joint therefor; a spring located within the ring support and having a narrow passage for the rod d between opposing walls 60 or faces; and a cap-plate H applied to said support and serving to retain the spring therein.

2. In a loose-leaf binder the combination with a suitable support, of divided rings the 65 members of which are independently pivoted in said support; a rod or wire passing through the overlapping ends of said members at a point between their pivotal supports; and a spring holding-device for maintaining the 70 ring members in their opened and closed positions, said holding-device having a narrow passageway for the rod formed by yielding or resilient walls, said passageway being widened at those points to which the rod or 75 wire is carried when the rings are fully opened or fully closed.

3. In a loose-leaf binder the combination with a cover and suitable support, of impaling rings, each comprising two members 80 hinged or jointed together at one end and independently pivoted in the support, said members having a knuckle-joint whereby the extent of their opening is limited and determined.

4. In a loose-leaf binder the combination with a cover and a suitable support attached thereto, of rings each comprising two members 85 hinged together at one end and pivotally mounted in the support; and a spring 90 arranged to bear against the pivot pin or rod connecting the ends of the rings and to hold the same in the different positions to which it is moved in the act of opening and closing the rings.

5. In a loose-leaf binder, in combination with a suitable support, impaling rings G, each comprising two members a, b pivotally mounted in said support; a hinge-rod or wire d connecting proximate ends of said 100 rings; and a spring I having flattened loop j, and branches k extending from said loop in substantially parallel planes and in close proximity, and thence branching or curving outward, substantially as shown.

In testimony whereof I have signed my name to this specification in the presence of two subscribing witnesses.

JOHN L. McMILLAN.
